DESIGN FOR A CAP FOR A WRITING
INSTRUMENT

Alexander Sydney Weston, New York, N. Y.

Application January 13, 1948, Serial No. 143,713

Term of patent 3½ years

(Cl. D74—1)

To all whom it may concern:

Be it known that I, Alexander Sydney Weston, a citizen of the United States, residing at New York, in the county and State of New York, have invented a new, original, and ornamental Design for a Cap for a Writing Instrument, of which the following is a specification, reference being made to the accompanying drawing, forming a part thereof.

Fig. 1 is a front elevational view of a cap for a writing instrument, showing my new design;

Fig. 2 is a top view thereof; and

Fig. 3 is a bottom view thereof.

I claim:

The ornamental design for a cap for a writing instrument, as shown.

ALEXANDER SYDNEY WESTON,
